Zachary T. Miller,

Royal E. Burnham,

Attorney

UNITED STATES PATENT OFFICE.

ZACHARY T. MILLER, OF BLISS, OKLAHOMA.

BLINDER.

1,406,675.

Specification of Letters Patent. Patented Feb. 14, 1922.

Application filed April 13, 1921. Serial No. 460,879.

To all whom it may concern:

Be it known that I, ZACHARY T. MILLER, a citizen of the United States, residing at Bliss, in the county of Noble and State of Oklahoma, have invented certain new and useful Improvements in Blinders, of which the following is a specification, reference being had therein to the accompanying drawing.

10 It is an object of this invention so to form a blinder of one piece of sheet metal that it may be associated adjustably with the cheek or other strap of a bridle without employment of other parts.

15 The invention further provides for the economical production of blinders by the stamping of blanks from sheet metal and the bending thereof to form the complete articles, which have guideways for the straps 20 and means for holding them adjustably therein.

When considered in connection with the description herein, the characteristics of the invention will be apparent from the accompanying drawings, forming part hereof, wherein embodiments of the invention are disclosed for purposes of illustration.

Although the disclosures herein exemplify what now are considered to be preferable 30 embodiments of the invention, it is to be understood that it is not the intention to be limited necessarily thereto in interpretation of the claims, as modifications and adaptations within the limits of the claims can be 35 made without departing from the nature of the invention.

Like reference-characters refer to corresponding parts in the views of the drawings, of which—

40 Fig. 1 is a side view of a blinder with straps attached thereto;

Fig. 2 is a longitudinal sectional view;

Fig. 3 is an edge view;

45 Fig. 4 is a plan view of the stamped out material of a blinder before bending; and Fig. 5 is a side view of a modification.

Having more particular reference to the drawings, 6 designates a cheek or other bridle-strap, with which is associated a 50 blinder 7.

The blinder is made of bendable sheet metal, which may be covered with leather or other suitable material, if desired, such covering not being shown herein, however, as 55 it does not pertain to this invention.

The invention provides in each blinder a

guideway or channel for cheek or other bridle straps, such guideway or channel being afforded by bending integral portions of the material after it has been cut or stamped 60 from stock in the manner hereinafter described.

For production of the form disclosed by Figs. 1, 2, 3, and 4, the stock is stamped or cut to afford at the upper and lower portions 65 of the blank two comparatively long extensions or ears 8 and a shorter extension or ear 9 between them, these extensions projecting from the edge at the strap side of what is to be the blinder. 70

The extensions are sufficiently long to be looped over and to afford, with the major portion of the material, overlapping guides. In the formation of these guides, the extensions 8 are bent outwardly from the material 75 at 8^a, then over as a web 8^b substantially parallel to the major portion of the material, and then toward the major portion at 8^c so that the free edges are brought into abutment with the material. 80

The intermediate extensions 9 are each formed with a central hole 10, through which is inserted a headed pin 11 constituting a strap engaging and holding member. Those extensions are bent over against the major 85 portion of the material and hammered or otherwise pressed closely thereagainst with the head of the pin under it.

That form of blinder is adapted particularly for association with a bridle in which 90 the cheek-strap is integral with and forms a part of the crown-strap, such a strap being connected to the blinder by having end portions inserted in the upper guideway afforded by the extensions 8, and with the pin 11 95 extending through one of the holes therein. In such a case, a looped strap 12 attached to a ring of the bit is connected similarly in the lower guideway, both end portions of the strap being brought into engagement with 100 the pin. However, such a blinder also is adapted to be associated with a single strap extending from one ring of the bit over the head and down to the other ring of the bit and through both guideways of each blinder. 105

The blinder shown by Fig. 5 is formed in a similar manner, except that it has one guideway-forming extension 8 in its upper portion and one in its lower portion, with the bent-over pin-holding member 9 substantially midway between them. 110

Such a blinder is adapted particularly for

association with a single strap connected in its end portions with the bit-rings, in which case the take-up free portions of the strap are brought into engagement with the pins under intermediate portions thereof, which also are held by the pins. However, by making the pins sufficiently long, the blinder of this form, as in the case of the first form described, may be used to connect free ends of cheek-straps and bit-loops by bringing the end portions of all of them into engagement with the pin.

It is unnecessary to use buckles or other separate fasteners to associate in a bridle blinders of the form shown and described, as the blinders themselves afford means whereby they may be connected to and adjusted on the straps at the places desired, the straps being inserted in the guideways and adjustment made by bringing the proper holes in the straps into engagement with the pins. Moreover, looped straps, such as those used for connecting the bit, may be connected with the blinder by bringing both free

end portions thereof into the guideways and 25 into engagement with the pins.

Having thus described my invention, what I claim as new, and desire to secure by Letters Patent, is—

1. A blinder of bendable sheet material 30 having strap-guides formed of integral ears looped back over the material, an intermediate integral ear between two of the guides bent back against the material, and a strap-engaging member extending from 35 said intermediate ear.

2. A blinder of bendable sheet material having strap-guides formed of integral ears looped back over the material, an intermediate integral ear having a hole therein bent 40 back and down against the material, and a headed strap-engaging member extending through said hole and having its head under said intermediate ear and against the portion of the material overlapped thereby. 45

In testimony whereof I affix my signature.

ZACHARY T. MILLER.
